ABSTRACT OF THE DISCLOSURE

An apparatus for processing elongated filaments includes feed means which feeds at least one elongated crimped filament of given cross section towards a filament processing station. A pair of cooperating pressure rollers are arranged at the processing station and the filament passes through the nip of these pressure rollers whereby the cross section of the filament is deformed transversely of the elongation thereof.

BACKGROUND OF THE INVENTION

The present invention relates generally to the treatment of elongated filaments, and more particularly to an apparatus for treating such elongated filaments. Still more particularly, the invention relates to an apparatus for processing crimped filaments and, more specifically, for processing crimped yarn.

Filamentary material, which term will hereafter be used to designate both single filaments and a multiplicity of filaments which have been united into a yarn, have a certain load-extension and recovery characteristic once they have undergone a crimping treatment. This characteristic is measured by suspending a load from a length of crimped filamentary material and measuring the amount to which it is longitudinally extended or stretched, and the recovery characteristic is the ability to contract which is expressed in percentages of the degree of extension. It is evident that the load-extension and recovery characteristic of filamentary material affects the range of applications to which such material may be put, and the characteristic behaviour of such material in a given application. From this it follows that it must be desirable to be able to affect the load-extension and recovery characteristics of filamentary material so as to "tailor" them to a specific requirement. This has, in fact, long been attempted but no satisfactory solutions have heretofore been proposed.

SUMMARY OF THE INVENTION

The present invention provides the aforementioned desired solution.

More particularly, the present invention provides for alteration of the load-extension and recovery characteristics of filamentary material.

Still more particularly, the present invention provides an apparatus for processing filamentary material whereby to alter the load-extension and recovery characteristics of such filamentary material.

The apparatus in accordance with the present invention is not at all complicated and is therefore simple and inexpensive to manufacture. Because of its lack of complexity the apparatus according to the present invention can readily be incorporated not only in processing machines for filamentary material which are being newly constructed, but can also be added to existing ones of such processing machines.

In accordance with one feature of my invention I provide an apparatus for the processing of elongated filamentary material, which apparatus comprises feed means and deforming means. The feed means is operative for

2

feeding at least one elongated crimped filament of given cross section in a predetermined direction to a filament processing station. The deforming means is arranged at the processing station and effects deforming of the filament transversely of the elongation thereof, thereby effecting permanent alteration of the cross-sectional configuration of the filament and a consequent alteration of the load-extension and recovery characteristics thereof.

The deforming means in the apparatus according to my present invention may comprise pressure-applying rollers which define a nip between themselves, through which nip the filamentary material passes. These rollers may, if desired, be heated, or at least one of them may be heated. Under certain circumstances, for instance if the filament which is being processed is possessed of latent crimp, a term which is well known in this field, my apparatus may also comprise heating means arranged upstream of the deforming means so as to develop the latent crimp. Of course, the apparatus may comprise a crimping device, for instance a false-twist crimping device, from which the crimped filament may be directly fed to the deforming means. This will facilitate continuous operation of my novel apparatus.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWING

The single figure illustrates in diagrammatic view an apparatus according to my invention.

DESCRIPTION OF THE PREFERRED EMBODIMENTS

Discussing now the drawing in detail it will be seen that I show a filamentary material 10 which may be a single crimped filament, or which may be a multi-filament material such as a crimped yarn. I provide feed means in form of feed rollers 11 which serve to advance this yarn or filament in the direction towards a pair of pressure rollers 12 which will be described subsequently. The yarn or filament in the direction towards a pair of pressure in which it is provided with a latent crimp. This crimp must then be developed and for this reason I provide the heater 14 which may be a conventional electrically heated curved plate type. The filament 10 passes over a surface of the heater 14 and the latent crimp in the yarn is developed. Of course, the heater 14 can also be provided for other reasons and it will be understood that it can be present even if the filament 10 does not contain latent crimp.

Another possibility is that the filament 10 is crimped in a suitable manner, for instance by a false-twist crimping device, upstream of the feed rollers 11. Such a device is not shown because it is well known to those skilled in the art and it is being mentioned here primarily to show the versatility of my novel apparatus which, quite obviously, can be employed in a variety of different ways for processing filamentary material coming from a variety of different sources, such as directly from a twisting device, from a storage package, or the like.

The filament 10 is forwarded by the feed rollers 11, at least one of which is driven in a suitable manner which is here not illustrated because it is well known to the art and entirely conventional, to a deforming means which in the illustrated embodiment consists of a set 12 of pressure-applying rollers. Individually these pressure-applying rollers are identified with reference numerals 12a and

12b, and again at least one of these rollers **12a** or **12b** is driven in a suitable and entirely conventional manner. In the embodiment illustrated the roller **12a** is fixedly mounted on a rotary shaft **13** which, it will be understood, may extend for a considerable distance and may carry a plurality of additional rollers **12a**. Evidently, the illustrated arrangement can be duplicated any desired number of times to provide a plurality of arrangements for simultaneously processing a plurality of individual filaments or a plurality of multi-filament structures. This is of importance if a textile machine with which the novel apparatus is to be used comprises a plurality of operating stations because each of the stations can be provided with an apparatus according to my invention.

The pressure rollers **12a** and **12b** consist of a wear-resistant hard material, such as steel, which is not subject to being scored by passage of the filament **10** over and between them. Whereas the roller **12a** is mounted for rotation on the shaft **13**, the second roller, namely the roller **12b**, is rotatably mounted for movement closer towards and away from the roller **12a** so that it engages the surface of the latter with a force which can be selected at the will of the operator. In the illustrated embodiment this adjustment possibility is provided by mounting the roller **12b** rotatable on a hydraulic ram means **16** which in turn is carried on a bracket **17** mounted on the textile machine. The ram means **16** which urges the roller **12b** against the roller **12a** and it will be understood that the pressure with which the roller **12b** is urged against the roller **12a**, and therefore the pressure which the two rollers together exert on the filament **10** passing therebetween, is adjustable by adjusting the pressure of the hydraulic fluid in the hydraulic ram means **16**. It will also be evident that a discussion of the hydraulic ram means as to its construction is not necessary because this is of course entirely conventional. If a plurality of apparatus such as illustrated in the drawing are provided for a common operation, that is if a multi-station machine is provided with a plurality of such apparatuses, one at each station, then the pressure applied by all the pressure applying rollers can advantageously be adjusted from a single source of hydraulic pressure.

As the filament **10** passes between the rollers **12a** and **12b** it is subjected to pressure which acts on it transversely of its elongation, whereby its cross section is permanently deformed, also in direction transversely to its elongation. Inasmuch as the filament **10** is crimped and thus consists of a plurality of longitudinally arrayed portions each of which extends transversely of the longitudinal extension of the filament and in a plane which is normal to this extension, there exists a natural tendency for each of these crimped portions to twist as it approaches the nip between the rollers **12a** and **12b**. As a result of this each crimped portion passes through this nip with its plane aligned with the line of contact between the rollers **12a** and **12b**. Therefore, the increase in the cross-sectional configuration of the yarn which results from the deformation pressure exerted by the rollers **12a** and **12b** takes place in the plane of each of the crimped portions, and this in turn results in a permanent change in the load-extension and recovery characteristics of the filament **10**.

Downstream of the rollers **12a** and **12b** a suitable take-up means **15** winds up the thus-processed filament.

I have found it advantageous to provide means for varying the peripheral speeds of the rollers of the first set **11** and the rollers of the second set **12** with respect to one another, thus making it possible to overfeed the filament **10** by reason of increasing the peripheral speed of the rollers **11** via that of the rollers **12**, or otherwise selecting the desired extension condition of the filament **10** between the rollers **11** and **12**. It may be here reiterated, as has already been suggested earlier, that the rollers **11** may supply the filament **10** from a suitable crimping device, for instance from a false-twist crimping device, and in fact

the rollers **10** may be the output feed rollers of a false-twist crimping device if desired.

It will also be obvious that the hydraulic ram means **16** is illustrated merely by way of example and that it can be replaced with other arrangements, for instance spring-loading means, weight-loading means or any other arrangement which will serve to bias the roller **12b** in the direction towards the roller **12a**. Clearly, of course, the relationship can also be reversed and the roller **12a** biased towards a roller **12b** which is mounted on a stationary axis. As far as heating of one or both of the rollers of the pair **12** is concerned, it will be evident that this can also be affected in a variety of well-known ways, for instance by embedding electric resistance heating elements in one or both of the rollers **12a** and **12b**.

It will be understood that each of the elements described above, or two or more together, may also find a useful application in other types of arrangements differing from the types described above.

While the invention has been illustrated and described as embodied in an apparatus for processing elongated filaments, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims:

1. Apparatus for processing elongated filaments comprising, in combination, feed means operative for feeding at least one elongated crimped filament of given cross-section in predetermined direction to a filament processing station; and deforming means arranged at said processing station and operative for engaging and deforming said filament from opposite sides transversely of the elongation thereof whereby to effect permanent alteration of the cross-sectional configuration of said filament and consequent alteration of the load extension and recovery characteristics thereof.

2. Apparatus for processing elongated filaments comprising, in combination, feed means operative for feeding in predetermined direction to a filament processing station at least one elongated filament of given cross-section and comprising a plurality of longitudinally arranged curved filament portions each of which extends transversely to the elongation of said filament; and deforming means arranged at said processing station and operative for deforming each of said filament portions transversely of the elongation of said filament so as to provide for each of said filament portions a cross-sectional configuration whose major dimension extends in the plane of curvature of the respective portion, thereby effecting permanent alteration of the cross-sectional configuration of said filament and consequent alteration of the load extension and recovery characteristics thereof.

3. Apparatus for processing elongated filaments comprising, in combination, feed means operative for feeding in predetermined direction to a filament processing station at least one elongated filament of given cross-section and comprising a plurality of longitudinally arranged curved filament portions each of which extends transversely to the elongation of said filament; and deforming means arranged at said processing station and comprising pressure-applying means operative for applying to said filament portions from opposite sides of the respective planes of curvature thereof a pressure requisite for deforming said filament so that its major cross-sectional

dimension extends in the plane of curvature of the respective filament portion, with the resulting permanent alteration of the cross-sectional configuration of said filament effecting consequent alteration of the load extension and recovery characteristics thereof.

4. Apparatus as defined in claim 3, wherein said pressure-applying means comprises a pair of pressure rollers defining with one another a nip through which said filament passes.

5. Apparatus as defined in claim 3, wherein said pressure-applying means comprises a pair of pressure rollers, at least one of which is driven, defining with one another a nip through which said filament passes.

6. Apparatus as defined in claim 5; and further comprising means for heating at least one of said pressure rollers.

7. Apparatus as defined in claim 5; and further comprising heating means arranged upstream of said pressure rollers and operative for heating said filament prior to deformation thereof.

8. Apparatus as defined in claim 1; and further comprising filament take-up means arranged downstream of said processing station and operative for taking up the deformed filament.

9. Apparatus for processing elongated filaments comprising, in combination, feed means operative for feeding at least one elongated crimped filament of given cross-section in predetermined direction in a filament processing station; and deforming means arranged at said processing station and operative for deforming said filament transversely of the elongation thereof whereby to effect permanent alteration of the cross-sectional configuration of said filament and consequent alteration of the load extension and recovery characteristics thereof, one of said means being constructed and arranged for effecting overfeeding of said filament to said deforming means.

10. Apparatus for processing elongated filaments comprising, in combination, feed means operative for feeding at least one elongated crimped filament of given cross-section in predetermined direction in a filament processing station; deforming means arranged at said processing station and operative for deforming said filament transversely of the elongation thereof whereby to effect permanent alteration of the cross-sectional configuration of said filament and consequent alteration of the load extension and recovery characteristics thereof; and false-twist crimping means for crimping said filament prior to feeding thereof to said processing station.

11. Apparatus as defined in claim 5, wherein said pressure-applying means further comprises adjusting means for moving at least one of said rollers towards and away from the other whereby to vary the nip defined by said rollers and to thereby adjust the deformation pressure exerted on said filament.
